CRUSHING MACHINE

Harold G. Edwards, Perry, Fla.

Application December 15, 1942, Serial No. 469,093

1 Claim. (Cl. 153—10)

My invention relates to improvements in crushing machines, the principal object in view being to provide an easily operative mechanism, for domestic or other use, in quickly crushing tin, or other metal, cans flat for compact storage in shipping to metal reclaiming plants and the like, and which is simple in construction involves few parts, is inexpensive to manufacture and install, and will not jam.

Other and subordinate objects are also comprehended by my invention, all of which, together with the precise nature of my improvements, will be readily understood when the succeeding description and claim are read with reference to the drawings accompanying and forming part of this specification.

In said drawings:

Figure 1 is a view in side elevation of my improved crushing machine in its preferred embodiment,

Figure 2 is a view in top plan,

Figure 3 is a view in vertical longitudinal section taken on the line 3—3 of Figure 2,

Figure 4 is a detail view in transverse section taken on the line 4—4 of Figure 2,

Figure 5 is a similar view taken on the line 5—5 of Figure 2, and

Figure 6 is a view in transverse section taken on the line 6—6 of Figure 2.

Referring to the drawings by numerals, in the illustrated embodiment thereof my improved crushing machine comprises an elongated, generally rectangular, frame including corner legs 1, horizontal, upper side and end cross bars 2, 3 connecting the legs 1 at the top of the frame, horizontal, lower side bars 4 connecting said legs 1 adjacent the bottom of the frame and horizontal side and end cross bars 5, 6 intermediate the bars 2, 3 and said bars 4, and further connecting said legs 1. The legs 1 and said bars are preferably formed of angle iron.

Extending horizontally from one end of the frame in a common horizontal plane with the intermediate side and end bars 5, 6 is a pair of opposed mechanisms supporting side plates 7, 8 converging relatively from the legs 1 at said end of the frame in spaced apart relation upon opposite sides of the median plane of said frame. One of the plates, for instance, 7, is fixed at one end, as at 9, to one leg, the other end of said plate being set into a rabbeted side edge 10 of a supporting block 11 and bolted, as at 12, to said block. The block 11 is welded, as at 13, to one of the end cross bars 6 in the center thereof and in upright position. The other plate 8 is hinged,

as at 14, to one leg 1 and has its other end slidably fitted in a rabbet 15 provided in the other side edge of the block 11, whereby said plate is swingable outwardly and inwardly of the frame and relative to the plate 7 for a purpose presently seen and limited as to inward swinging by a shoulder 16 forming part of the rabbet 15.

A pair of opposed crusher discs 17, 18 are mounted on the plates 7, 8 to rotate between said plates on suitable axis members 19 extending at right angles from the plates 7, 8. The discs 17, 18, as will be seen, converge in correspondence with the plates 7, 8 into close proximity at one end of the frame and are provided with conical opposed working faces 20 which, by virtue of the convergence of the disc, present peripheral portions upon one side of the axes of the disc spaced close together to form a bight in the horizontal center of the discs for crushing cans fed between 20 said discs.

A gravity feed, rectangular hopper 21 is suitably mounted by cross bars 22 at the top of the frame to depend between said working faces 20 of the discs 17, 18. Preferably the hopper 21 is provided with end walls 23 inclining downwardly between said discs 17, 18 in the direction of rotation of the latter, which is clockwise, as indicated by the arrows in Figures 1 and 3. The edges of the end walls 23 converge downwardly to fit in between the working faces 20 above the described bight of said discs.

Backing rollers are provided for the discs 17, 18 to prevent undue strain on the axis members 19 thereof. Preferably, for this purpose, a pair of upright bars 25 are suitably fixed to the outer sides of the plates 7, 8 opposite the bight of the working faces 20, each bar having a suitably mounted thereon a pair of upper and lower rollers 24 adapted to bear against the outer face of the adjacent disc adjacent the bight of the discs. On the other side of the axes of the discs 17, 18 a single roller 24 suitably mounted on the appropriate plate 7 or 8, as the case may be, bears against the outer face of the disc.

Backing rollers are provided for the discs 17, 18 to prevent undue strain on the axis members 19 thereof. Preferably, for this purpose, a pair of upright bars 25 are suitably fixed to the outer sides of the plates 7, 8 opposite the bight of the working faces 20, each bar having a suitably mounted thereon a pair of upper and lower rollers 24 adapted to bear against the outer face of the adjacent disc adjacent the bight of the discs. On the other side of the axes of the discs 17, 18 a single roller 24 suitably mounted on the appropriate plate 7 or 8, as the case may be, bears against the outer face of the disc.

Cushion springs 26 urge the plate 8 inwardly and the disc 18 toward the disc 17. Preferably, a pair of such springs are arranged between the ends of the bar 25 carried by the plate 8, and the ends of a similar bar 27 opposed to the bar 25 and fast on a support 28 suitably fixed in the frame. The bar 27 and opposed bar 25 are provided with spring seating sockets 29 of the usual type.

Means for driving the discs 18, 19 are provided as follows: An electric motor 30 is mounted on

a bed plate 31 supported by the side bars 4 at the side of the axes of the discs opposite to the bight of said discs. A cross shaft 32 is suitably mounted at its ends in the plates 7, 8 to extend across the edge of the discs 17, 18 at their most widely spaced point. The mounting for one of the shaft 32 comprises a bearing 33 in which the shaft 32 is slidable and which is swiveled on the plate 8, as represented at 34, to compensate for swinging of said plate. A pair of beveled gears 35 fast on the shaft 32 mesh with similar peripheral gear teeth 36 formed on the discs 17, 18. The armature shaft 37 of the motor 30 is operatively connected to the shaft 32 by a sprocket and chain drive 38.

The operation of the invention will be readily understood. The cans to be crushed are placed in the hopper 21 to feed into the bight of the discs 17, 18 where, under rotation of the latter by the described drive means, said cans are crushed and flattened out to be discharged downwardly from between said discs. The disc 18 is floatingly mounted by means of the hinged supporting plate 8 to yield outwardly in opposition to the springs 26 so that said discs cannot become jammed by the passage of cans through the bight formed thereby. Any suitable controls may be provided for the motor 30. It is contemplated that the teeth 36 on the disc 18 and those of the bevel gear 35 meshing with said 30

teeth be formed in the proper length to constantly mesh in sliding engagement during lateral movement of the plate 8 and disc 18.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claim.

What I claim is:

In a machine for crushing cans and the like, a frame, a pair of crusher discs having conical working faces and rotatably mounted in said frame in side-by-side converging relation to dispose said faces close together on one side of the axes of rotation of the discs to form a horizontal bight to which the cans may be fed, and means to rotate said discs in unison, the mounting for one of said discs comprising a swingably mounted plate yieldable to permit said disc to move laterally away from the other disc and prevent jamming of the discs by the cans, said means comprising peripheral teeth on said one disc and a power driven gear constantly meshing with the teeth on said disc during lateral movement of said disc.

HAROLD G. EDWARDS.
